UNITED STATES PATENT OFFICE.

OSWALD E. BECKMAN, OF MEDIAPOLIS, IOWA.

AIR-VENT ATTACHMENT.

Application filed June 1, 1922. Serial No. 535,082.

To all whom it may concern:

Be it known that I, OSWALD E. BECKMAN, a citizen of the United States, residing at Mediapolis, in the county of Des Moines 5 and State of Iowa, have invented certain new and useful Improvements in an Air-Vent Attachment; and I do hereby declare the following to be a full, clear, and exact description of the invention, such as will enable others skilled in the art to which it 10 pertains to make and use the same.

This invention relates to an air vent attachment for receptacles.

It is aimed to provide a novel, simple, inexpensive and readily attachable means for receptacles for cans of various sizes and shapes whereby air may be admitted thereto for coaction with the contents during pouring or dispensing thereof from the receptacle.

The invention resides in the novel arrangement, combinations and details of the parts as illustrated by one practical embodiment in accompanying drawings and hereinafter described.

In said drawings:—

Figure 1 is a view illustrating my attachment in use on a receptacle, the latter being shown in section, the attachment being illustrated in full lines in closed position and in dotted lines in an open position, and

Figure 2 is a perspective view showing the different elements comprising the attachment in disassociated relation.

Like reference characters designate like or similar parts in each view.

A receptacle is illustrated at A from which the contents are adapted to be removed by pouring through an outlet spout or opening 40 at B. As is well known in cans or receptacles of this general type, in view of the fact that there is no air inlet, it is difficult to rapidly and evenly pour or dispense the liquid. The present invention overcomes 45 such objection as it affords a means whereby the can will be ventilated or air admitted to assist in the flow of the contents therefrom.

In reducing the invention to practice, a suitable opening as at C is provided at an 50 appropriate part of the can A and a mounting plate 10 is disposed thereover and has a central vent opening 11 therethrough. The mounting plate may be of any suitable material, for instance tin, which renders it 55 bendable so as to conform to the contour of the engaged part of the can. The plate

10 may be secured in place in any suitable manner, as by means of soldering about its edge to the wall of the can, as the latter is of a tin composition or other metal. 60

In instances where the attachment is built into the can initially, the plate 10 may form the wall of the can, thus overcoming the necessity of employing a separate plate 10 as illustrated. 65

Slidable through the opening 11 and of less diameter than the opening is a stem at 12. Rigid with the stem and disposed below the plate 10 is a closure element or disc 13, on which a rubber or other washer or gasket 70 14 may be placed for direct contact against the underside of the plate 10 about the opening 11 in order to close said opening hermetically. A contractile coil spring 15 surrounds the stem 12 and closure element 13, 75 being soldered or otherwise secured to the plate 10 at one end, and at its other end having a pin 16 passing intermediate coils thereof and removable through an opening 17 in the stem. 80

A manipulating knob or cap 18 is provided exteriorly of the receptacle preferably screw threaded to the stem as at 19 for attachment and detachment to facilitate assembly of the plate 10 on the stem 12. 85

A detent notch 20 is provided on the stem 12 to engage the plate 10 about the opening 11. Said plate 10 about said opening 11 is preferably increased in thickness or reinforced as suggested at 21. 90

In use, the contraction of the spring 15 normally maintains the gasket 13 in engagement with the plate 10 thus hermetically sealing the can about the opening 11. The contents of the can are poured for instance 95 through the spout B, as knob 18 is depressed accordingly depressing stem 12 against the tension of the spring 15 and the closure element 13 and its washer 14, thus uncovering the opening 11, which due to the fact that it 100 is larger than the diameter of the stem serves as a vent opening for inlet of air. When the parts have been depressed sufficiently, the notch 20 is opposite the reinforcement 21 whereupon the knob may be slightly tilted 105 so that the notch will engage said portion 21 and remain in that position due to the contractile action of the spring. Such off-set disposition of the stem within the opening 11 also provides a larger vent for ingress of 110 air. When the contents of the can have been dispensed, knob 18 may be moved lat-

erally to disengage the notch 20 from enlargement 21 whereupon the parts will be restored to normal position by the spring 15.

I am aware of the fact that in dispensing the contents of cans, for instance oil cans, that the cans are punctured by means of a nail or otherwise to permit the ingress of air. Such puncturing however renders the can objectionable for general use thereafter 10 in carrying water, oil or the like, especially in a vehicle since it splashes or emerges from such a vent opening. In such a can, my attachment when used will overcome the spilling or escape of the contents through 15 the vent opening.

As merely one practical embodiment has been illustrated and described, it is to be understood that changes in the details may be resorted to provided they fall within the 20 spirit and scope of the invention.

I claim as my invention:—

1. A vent means for a receptacle consisting of a mounting plate provided with a vent opening therethrough, a stem movable 25 in said opening, a closure element on said

stem for coaction with the opening, a contractile spring associated with said stem to maintain the closure element in a closed position, means operable to depress said stem, and means on the stem engageable with said element adjacent said opening to maintain the stem depressed and the closure element accordingly in open position. 30

2. A vent means for a receptacle, consisting of a mounting plate provided with a vent opening therethrough, a stem for depression in said opening, a closure element on said stem, a contractile spring secured to said stem and to said plate to urge said closure element into contact with the plate, and 35 said stem having a notch to engage said plate about said opening to maintain the closure element depressed against the tension of said spring. 40

In testimony whereof I affix my signature 45 in presence of two witnesses.

OSWALD E. BECKMAN.
